ASSIGNORS TO ELIASON MANUFACTURING COMPANY, OF WILMINGTON, DELA-
WARE, A CORPORATION OF DELAWARE.

MACHINE FOR FORMING HEEL-LINING INSERTS FOR BOOTS AND SHOES.

1,118,541.

Specification of Letters Patent. Patented Nov. 24, 1914.

Application filed March 20, 1911. Serial No. 615,461.

To all whom it may concern:

Be it known that we, EDWIN H. ELIASON and GEORGE H. ZIEGLER, citizens of the United States, residing in Philadelphia, Pennsylvania, have invented certain Improvements in Machines for Forming Heel-Lining Inserts for Boots and Shoes, of which the following is a specification.

The object of this invention is to construct a machine for rapidly and accurately forming a heel lining insert adapted for use in boots and shoes. This insert is to be used when the lining at the heel is worn and by inserting this lining in a shoe in which the original lining is worn, it takes the place of the original lining and prevents the wearing away of the stocking and materially increases the life of the shoe.

In the accompanying drawings: Figure 1, is a side view of our improved machine for forming the heel lining insert; Fig. 2, is a sectional plan view on the line 2—2 Fig. 1; Fig. 3, is an enlarged front view of the upper portion of the machine; Fig. 4, is a sectional view on the line 4—4 Fig. 3; Fig. 5, is a detached view of the U-shaped press plate; Fig. 6, is a detached perspective view of the form on which the blank is stretched; Fig. 7, is a perspective view of the die and arms; Fig. 8, is a perspective view of the U-shaped plate; Figs. 9, 10 and 11, are diagram views illustrating different steps of the process; Fig. 12, is a sectional view on the line 12—12 when the parts are in the position illustrated in Fig. 11; Figs. 13, 14 and 15 are views showing the different steps in the process; Fig. 16, is a perspective view of the metallic stiffeners; Fig. 17, is a perspective view of the heel insert with the metallic stiffener in place, and Figs. 18 and 19 are perspective views of the finished heel insert.

A is the base of the machine supported on suitable legs *a* and mounted on this base is a form B made hollow as shown. Within the form is a suitable gas burner *b*² connected to a gas supply pipe *b*³, for heating the form to the proper degree. The upper surface of the form is rounded, as illustrated, to conform to the shape of the back of the shoe, while the front is flat so as to receive the sole piece to which the body of the heel insert is secured. On the front is a projection having a beveled groove *b* to

receive the end of the sole piece *x*' and a pin *b*' projects from the form on which the sole piece is forced. The sole piece is thus held vertically against the form.

Projecting from the base A are two posts C, C having bearings *c* for a transverse shaft C' on which is mounted an arm C² and this shaft is turned by means of a handle *c*' and is preferably counterbalanced by a weighted arm *c*².

Adapted to slide vertically on the posts C—C is a cross head D. This cross head is connected to the arm C² by longitudinally adjustable links D'. In the present instance, each link consists of two threaded sections and a turn buckle connects the sections, so that on turning the turn buckle the cross head can be adjusted toward or from the form B. Secured to the cross head are bearings *d*—*d* for vertical rods *e*—*e* attached to the die E, which conforms to the shape of the upper surface of the form B. Springs *e*' are mounted on the rods *e* between the die and the bearing *d* and tend to press the die toward the form. The downward movement of the die is limited by the nuts *e*² on the ends of the rods coming in contact with the bearings.

Adapted to slide laterally under the side of the cross head D are two bearings F—F. Each of these bearings is slotted for the reception of a pin *f* and are normally held away from the center of the head by springs *f*'. Pivotedly mounted on each sliding bearing F are arms F', which are shaped to conform to the sides of the form B and are beveled at the end to form wedges so that they will pass between the form and the press rolls *g*—*g* which are, in the present instance, mounted on plungers G—G adapted to bearings G'. Back of each plunger G is a coiled spring *g*', which tends to force them toward the form B. The plungers G have extensions which pass through caps *g*² and are provided with nuts *g*³. By adjusting the caps on the bearings G', the inner position of the rolls *g* can be regulated according to the size of the form used, as it will be understood that there must be a series of forms for the different sized heel inserts to be made. At the front of the machine is a bearing H' in which is mounted a plunger H carrying a pressure roll *h*. A spring *h*' is mounted between the plunger

and an adjustable cap h^2 and on the end of the stem of the plunger, which extends through the cap, are adjusting nuts h^3 .

Adapted to slide on standards I is a cross head I', which is connected by rods $i-i$ to a bar I² under the base A and this bar is in turn connected by a link J to a lever J' pivoted to a depending bearing A' at a' . The lever is in turn connected by a link J² to a foot lever J³, also pivoted to the bearing A'. On operating the foot lever the cross head I' will be drawn down. Springs i' mounted on the rods I and between the cross head and the base A, tend to force the cross head up as soon as the foot lever is released.

Pivoted at n to the cross head in line with the form B is a plate N. On this plate N is a U-shaped plate n' which turns the projecting flange of the blank of the heel insert against the sole piece x' . This U-shaped plate is beveled so that when it is forced down it crimps the flange of the blank and as it passes the rolls h it is forced toward the form and in turn presses the inturned flange against the cemented surface of the sole piece.

In order to push the rolls $g-g$ back from the form G, we provide two levers M, pivoted at m to bearings on the base A, and these levers are connected to the ends of the plungers G and in the lower ends of the levers are inclined slots m' into which extend pins $p-p$ of a two-armed lever P carried by a shaft P' mounted in bearings secured on the under side of the base A. The operating handle P² is attached to the shaft within easy reach of the operator so that on turning the shaft the plungers G—G and the rolls move away from the form.

In order to move the roll h and its plunger H away from the form, we provide a cam m^2 on one of the arms M which acts upon an arm H² attached to the plunger H so that on operating the lever M the plunger will be retracted against the pressure of its spring.

$s-s$ are platforms mounted on the bearings G' in the present instance and shaped to receive the ends of the body blank x which forms the back of the side portions of the heel insert, and hold it central over the form.

This machine does not finish the entire heel insert, but shapes it and places the parts in the proper position so that they can be readily finished by hand or upon another machine.

The operation of the machine is as follows:—The blank x forming the body of the heel insert is subjected to moisture to make it pliable and to allow it to be stretched over the form. We prefer to place the blank in a steam box at one side of the machine, but any other suitable moistening

means may be employed. The body blank is then placed on the form B, the edges resting on the platforms $s-s$ and above the rolls g . The sole piece x' is cemented on one face and placed in position at the end of the form. The shaft C is then turned through the medium of the handle c' and the head D is moved toward the form B. The arms F', as they move downward, press the side portions of the blank x against the rollers g, g , and stretch the blank over the form B.

The overhanging edges of the blank x are tucked in against the cemented surface of the heel piece by the U-shaped plate as it is drawn down by the treadle J³, between the roll h and the form B, forcing the inturned edges of the blank x against the blank x' and holding it there while the cement sets, after which the parts are released and the formed heel insert is removed from the machine. The back section x is stitched to the heel piece x' . The metallic stiffeners X² Fig. 16, are then placed in the pockets x^3 formed in the sections x and the projecting ends of the material forming the pockets are turned onto the heel piece, after which the fabric base section x^4 is cemented to the bottom of the heel insert, Fig. 18, making the complete article, as in Fig. 19. 95

We claim:

1. The combination in a machine for forming heel inserts, of a form on which the blank is mounted; a cross head; a die yieldingly mounted on the cross head above the form; arms on the cross head for forcing the blank over the form; means for moving the cross head; pressers located in the path of the arms for forcing them against the form; and means for holding the inturned edges of the body blank against a sole piece previously placed at the end of the form.

2. The combination in a machine for forming heel inserts, of a form upon which the body blank and the sole piece for the heel insert are mounted; a die shaped to conform to the body blank; a pivoted arm on each side of the die; means for moving the die and the arms down on to the form, the arms having a greater movement than the die; means for holding the sole piece on to the form; a movable plate at the end of the form; and means for moving said plate so that it will force the inturned portions of the body blank against the sole piece.

3. The combination in a machine for forming heel inserts, of a form; means for attaching a sole piece at the ends of the form; platforms at each side of the form adapted to support the ends of a blank mounted on the form; a cross head located above the form; a die carried thereby; arms pivoted to the cross head and extending on 130

- each side of the die; a spring mounted between the cross head and the die; yielding pressers on each side of the form; the parts being so arranged that when the cross head
- 5 is moved toward the form the die will hold the blank into the form and the arms will force the sides of the blank down under tension; and means for in-turning the ends of the blank for holding the said ends
- 10 against the sole piece.
4. The combination in a machine for forming heel inserts, of a form; means for attaching a sole blank to the end of the form; a platform at each side of the form for the
- 15 support of a body blank; vertical posts; a cross head mounted to slide on said posts; a shaft; an arm on the shaft; a rod connecting the arm with the cross head; means for operating the rod; a die mounted on the
- 20 cross head and shaped to conform to the upper surface of the form; a spring for allowing the die to yield after it has come in contact with the form; two pivoted arms carried by the cross head, tapered at the
- 25 lower ends and shaped on the inside to fit the side of the form; spring plungers acting to press the said arms against the form; and means for holding the inturned end of the body blank against the cemented surface of the sole piece after said body blank
- 30 has been clamped to the form.
5. The combination in a machine for shaping heel inserts, of a form; means for attaching a sole piece to the end of the
- 35 form; platforms at each side of the form for holding the lateral extensions of the body blank while resting on the form; a cross head; means for reciprocating the cross head; a spring-pressed die mounted
- 40 on the cross head and adapted to bear upon the form; pivoted arms mounted on the cross head, the inner ends of said arms being shaped to conform to the sides of the form; the outer surface of the arms being
- 45 tapered; spring-actuated plungers having rolls for forcing the arms toward the form and thereby stretching and binding the body blank against the sides of the form; means for holding the inturned edges of the body
- 50 blank against the cemented surface of the sole piece; and means for retracting the plungers.
6. The combination in a machine for forming heel inserts, of a form; means for attaching a sole piece to the end of the
- 55 form; supports for the ends of a body blank when it is applied to the form; standards; a cross head mounted to reciprocate on the standards; means for reciprocating said
- 60 cross head; sliding bearings on the cross head; arms pivotally mounted on the sliding bearings and extending on each side of the form; means for forcing the ends of
- the arms toward the form when the cross head is lowered; and springs for retracting the sliding bearing when the parts are released.
7. The combination in a machine for forming heel inserts, of a form; means for attaching a sole piece to the end of the
- 65 form; means for supporting a body blank on the form; a spring-pressed die bearing upon the top of the form; pivoted arms; means for forcing said arms down past the form; means for causing said arms to press
- 70 upon the form; a cross head; a plate carried by the cross head and adapted to bear upon the inturned ends of a body blank at the end of the form; and a spring plunger arranged to bear against the plate and to
- 75 hold it in contact with the blank.
8. The combination in a machine for forming heel inserts, of a fixed form; a spring-pressed die mounted above the form; pivoted arms depending on each side of the
- 80 die and adapted to force a blank tightly on the form below the die; side pressure plungers having rolls bearing upon the outside of said arms; a plate bearing against the end of the form; means for moving the said
- 85 plate vertically; a spring-pressed plunger adapted to rest against the plate and force it toward the form; and means for moving the plunger back so that the arms and the plate can be returned to their normal positions.
9. The combination in a machine for forming heel inserts, of a hollow form; a burner within the form whereby the said form is heated, a spring-pressed die mounted above the form, the lower end of the die conforming to the shape of the form; pivoted arms on each side of the die for holding the extension of a body blank against the form; and means for pressing
- 95 the inturned edges of the body blank against the cemented surface of a sole piece located at the end of the form.
10. The combination in a machine for forming inserts, of a form upon which the
- 100 body blank for the heel insert is mounted; a die for drawing the body blank over the form; a U-shaped plate; and means for moving the plate downward, the plate being shaped to draw the overhanging end of
- 105 the body blank and force it against a sole piece located at the end of the form.

In testimony whereof, we have signed our names to this specification, in the presence of two subscribing witnesses.

EDWIN HOLT ELIASON.
